Primary Examiner — Richard E Chilcot

(57) **CLAIM**

The ornamental design for a portable glassware rinsing apparatus, as shown and described.

DESCRIPTION

FIG. 1 is a front-top-left perspective view of a portable glassware rinsing apparatus showing my new design; FIG. 2 is a front elevational view, thereof; FIG. 3 is a rear elevational view thereof; FIG. 4 is a right elevational view thereof; FIG. 5 is a left elevational view thereof; FIG. 6 is a top plan view thereof; FIG. 7 is a bottom plan view thereof; FIG. 8 is a front elevational view of a portable glassware rinsing apparatus with the access door open; FIG. 9 is a front-top-left perspective view of a portable glassware rinsing apparatus with the access door open; and, FIG. 10 is a front-top-left perspective view of a portable glassware rinsing apparatus with the storage tanks pulled out of the apparatus.

The broken line showing of the handles and storage tanks in FIGS. 1–10 are included for the purpose of showing environmental structure and form no part of the claimed design.

1 Claim, 10 Drawing Sheets
